CLAIM

We claim the ornamental design for a cutlery block, as
shown and described.

DESCRIPTION

FIG. 1 is a top perspective view of a cutlery block of the
present disclosure;

FIG. 2 is a first side elevational view of the cutlery block of
FIG. 1;

FIG. 3 is a second side elevational view of the cutlery block
of FIG. 1;

FIG. 4 is a third side elevational view of the cutlery block
of FIG. 1;

FIG. 5 is a fourth side elevational view of the cutlery block
of FIG. 1;

FIG. 6 is a top plan view of the cutlery block of FIG. 1; and,
FIG. 7 is a bottom plan view of the cutlery block of FIG. 1.
The broken lines depict portions of the article that form no
part of the claimed design.

1 Claim, 7 Drawing Sheets
